(57) **CLAIM**

The ornamental design for a protective packaging kit, as shown and described.

DESCRIPTION

FIG. 1 is a top front perspective view of the protective packaging kit showing my new design;

FIG. 2 is front elevation view of thereof, with a rear elevation view being a mirror image of the front elevation view;

FIG. 3 is a top elevation view thereof;

FIG. 4 is a bottom elevation view thereof; and,

FIG. 5 is a right elevation view thereof, with a left elevation view being a mirror image of the right elevation view.

The broken lines shown in the drawings depict portions of the article that form no part of the claimed design. The protective packaging kit is shown with a symbolic break in its length, width, and height in FIGS. 1-5, represented by break lines. The break lines and appearance of any portion of the article between the break lines form no part of the claimed design.

1 Claim, 3 Drawing Sheets
